We claim the ornamental design for a handle for a covering for an architectural opening, as shown and described.

DESCRIPTION

FIG. 1 is an isometric view of a handle for a covering for an architectural opening in accordance with a first embodiment of the present design.

FIG. 2 is a first side view thereof.

FIG. 3 is a second side view thereof.

FIG. 4 is a third side view thereof.

FIG. 5 is a fourth side view thereof.

FIG. 6 is a first end view thereof.

FIG. 7 is a second end view thereof.

FIG. 8 is an isometric view of a handle for a covering for an architectural opening in accordance with a second embodiment of the present design.

FIG. 9 is a first side view thereof.

FIG. 10 is a second side view thereof.

FIG. 11 is a third side view thereof.

FIG. 12 is a fourth side view thereof.

FIG. 13 is a first end view thereof.

FIG. 14 is a second end view thereof.

FIG. 15 is an isometric view of a handle for a covering for an architectural opening in accordance with a third embodiment of the present design.

FIG. 16 is a first side view thereof.

FIG. 17 is a second side view thereof.

FIG. 18 is a third side view thereof.

FIG. 19 is a fourth side view thereof.

FIG. 20 is a first end view thereof.

FIG. 21 is a second end view thereof.

FIG. 22 is an isometric view of a handle for a covering for an architectural opening in accordance with a fourth embodiment of the present design.

FIG. 23 is a first side view thereof.

FIG. 24 is a second side view thereof.

FIG. 25 is a third side view thereof.

FIG. 26 is a fourth side view thereof.

FIG. 27 is a first end view thereof; and,

FIG. 28 is a second end view thereof.

The dash-dash broken lines illustrate features of the handle for a covering for an architectural opening and environment in which the handle may be used that form no part of the claimed design. The dash-dot-dash broken lines illustrate a boundary between claimed features and non-claimed features.
